UNITED STATES PATENT OFFICE.

WILLIAM ELLSWORTH ROBERTS, OF KENOSHA, WISCONSIN.

BUTTON-LINK.

1,335,703.

Specification of Letters Patent. Patented Mar. 30, 1920.

Application filed November 25, 1919. Serial No. 340,689.

To all whom it may concern:

Be it known that I, WILLIAM E. ROBERTS, a citizen of the United States, residing at Kenosha, in the county of Kenosha and State of Wisconsin, have invented new and useful Improvements in Button-Links, of which the following is a specification.

This invention relates to fastenings for cuffs and collars, such as are or may be worn by either ladies or gentlemen, and the object thereof is to provide an improved device of this character which will operate to maintain the approved shape of the cuff or collars, as the case may be, while insuring comfort to the wearer and at the same time affording unusual facilities for ornamentation.

Hitherto it has been the practice to attach the meeting ends of cuffs or collars to each other by means of various holding devices, as cuff-buttons, collar-buttons, and link-buttons. The last-named form of holder has been particularly in vogue for cuffs in recent years, the chief characteristic thereof consisting in the employment of a pair of outwardly-exposed buttons showing over the button-holes, and a more or less concealed link connecting the buttons. The present invention contemplates a reverse arrangement, wherein the buttons will be kept out of view, whereas the link or links uniting the same will have a full exposure.

Referring to the drawing hereto annexed, which forms a part of this specification, and in which like numerals denote corresponding elements throughout the various views:

Figure 1 is a full front view of a button-link, applied to a collar.

Fig. 2 is a side view of the button-link shown in Fig. 1, the same being removed from the collar.

As represented, the improved button-link disclosed herein comprises two flat members A¹, A², which are duplicates one of the other and can be used interchangeably. The said members are each provided at one end with two hinge ears, a¹—a¹, a²—a².

Each link member aforesaid is designed to carry one of a pair of buttons, as B¹ B². The latter may be formed integral each with its respective link member A¹ or A², or attached thereto in any convenient or preferred manner as for instance by studs b¹ b². In accordance with this invention, however, the buttons are placed, in each instance, on that face of the corresponding member

whereon the ears for the hinge are made to project. Constructed in this fashion, the device can be applied externally, in such a manner that the buttons will pass inward through the holes and will remain covered, whereas the link itself will stay in full sight, partly encompassing the meeting ends of the collar or cuff.

It need scarcely be pointed out that the broad expanse of the outer surface of the flat members composing the link lends itself to ornamentation and display in a degree far superior to what is possible with the antiquated form of outwardly exposed buttons. The said outer surface of the link further permits the engraving thereon of something more than initials or monograms. It admits of the writing of full names and connected inscriptions, such as expressions of esteem and the like.

Both ends of the link, it will be noticed, are made to extend some distance beyond their respective buttons. This is done for a two-fold purpose. First, the extension prevents the collar or cuff from buckling, which it would be liable to do, where the buttons located at or near the ends of the link, as is customarily done. Secondly, the extended ends of the link completely overlie the button-holes and therefore conceal the more or less ragged or distorted slits which a collar or cuff that has been laundered a few times is likely to expose to view.

The construction illustrated affords a great degree of adjustability. The flat members A¹ A² are separately hinged, and they are further connected to and by centrally-pivoted leaves C¹ C², to which the link members A¹ A² are respectively hinged, and which leaves are superimposed, as best seen in Fig. 2. The two leaves C¹ C² are held together (and with them the members A¹ A²) by means of a stud D, the stem of which passes through suitable registering holes in said leaves. The stud, it will be observed, can have a diamond or other gem E mounted thereon. It will also be observed that the stud D acts as a pivot for the leaves C¹ C².

Having described my invention, what I desire to secure by Letters-Patent and claim is:

1. In an article of manufacture of the character described, the combination of two button carrying members, and buttons fixed to and extending inwardly at an angle to

said members, of intermediate leaves hinged one to each of said members, and means pivotally connecting said leaves in a different plane from that of the members.

- 5 2. In an article of manufacture of the character described, the combination of two button carrying members, and buttons fixed to said members and extending inwardly from the inner faces of the members intermediate of the ends thereof, of a leaf hinged to each of said button carrying members, and a stud pivotally connecting said leaves so as to afford them and said members angular adjustment in various planes.
- 10 3. In an article of manufacture of the character described, the combination of two button carrying members, and buttons fixed to said members and extending inwardly from the inner faces of the members intermediate of the ends thereof, of a separate hinge for each of said members, and a pivot transverse to said hinges for adjusting their axes at various angular inclinations to each other.
- 15 4. In an article of manufacture of the character described, the combination of two

button carrying members, and buttons fixed to said members and extending inwardly from the inner faces of the members intermediate of the ends thereof, of a link having a separate hinge for each of said members, and pivotal means for setting the axes of said hinges at various angular inclinations to each other, said means extending in a plane transverse to the planes of the 30 hinges.

5. In an article of manufacture of the character described, the combination with a pair of button carrying members, and buttons fixed to said members and extending 40 inwardly from the inner faces of the members intermediate of the ends thereof, of superposed leaves therebetween separately hinged one to each member, said leaves having central apertures registering one with 45 the other, and a stud passed through said apertures holding both said button carrying members and leaves adjustably together.

In testimony whereof I affix my signature.

WILLIAM ELLSWORTH ROBERTS.
